(57) **CLAIM**

The ornamental design for a tape for tape printing machine, as shown and described.

DESCRIPTION

FIG. 1 is a perspective view of a tape for tape printing machine;

FIG. 2 is a front view thereof;

FIG. 3 is a top view thereof;

FIG. 4 is a left-side view thereof;

FIG. 5 is a right-side view thereof;

FIG. 6 is a rear view thereof;

FIG. 7 is a bottom view thereof;

FIG. 8 is a cross-sectional view taken along a line 8-8 in FIG. 3; and,

FIG. 9 is a cross-sectional view taken along a line 9-9 in FIG. 3.

The broken lines depict environmental subject matter only and form no part of the claimed design.

1 Claim, 3 Drawing Sheets

FIG. 8

FIG. 9
